STORAGE CONTAINER FOR SHOES

David H. Fiel, 2318 Baylis Ave., Elmont, N.Y. 11003

Filed Nov. 12, 1969, Ser. No. 20,035

Term of patent 7 years

Int. Cl. D6—01

U.S. Cl. D33—3

FIG. 1 is a perspective view of the storage container for shoes embodying the features of my new design,

FIG. 2 is a top plan view thereof, and

FIG. 3 is a side elevational view thereof.

The sides of the rack not shown are the same in appearance as the side shown in FIG. 3.

I claim:

The ornamental design for a storage container for shoes, substantially as shown and described.
